UNITED STATES PATENT OFFICE.

ADELMER M. BATES, OF CHICAGO, ILLINOIS, ASSIGNOR TO BATES VALVE BAG COMPANY,
OF CHICAGO, ILLINOIS, A CORPORATION OF WEST VIRGINIA.

BAG-TIE.

1,156,265.

Specification of Letters Patent

Patented Oct. 12, 1915.

Application filed December 29, 1913. Serial No. 809,216.

To all whom it may concern:

Be it known that I, ADELMER M. BATES, a citizen of the United States, residing at Chicago, in the county of Cook and State of Illinois, have invented a certain new and useful Improvement in Bag-Ties, of which the following is a specification.

My invention relates to a wire tie for bags, particularly open mouth bags, and has for its object to provide certain new and useful improvements more particularly hereinafter set forth.

It is illustrated in the accompanying drawings wherein—

15 Figure 1 is a side elevation of a tie; Fig. 2, an end view of a bag showing the tie in position for tightening; and Fig. 3, a similar view showing the tie tightened on the bag.

20 My tie, broadly speaking, comprises a length of wire with a large loop at one end, a smaller loop at the other and a return length of the wire, the two parts twisted together adjacent the small loop. When the tie is to be applied to the bag it is brought around the part to be closed and the small loop is carried through the large loop and the small end drawn out so as to tightly close the bag portion, and then the twisted 25 or doubled portion of the tie is bent backward on the large loop so as to tightly secure the parts together. In the preferred form of my device the two lengths of wire are twisted together as indicated in Fig. 1 30 so that each piece of the wire is twisted, or rather they are arranged so that the body of the tie is straight and the return end is coiled around the body of the tie so as to make a kind of screw thread or notched 35 portion.

One of the advantages of my tie is that it is capable of being applied and detached by hand without the use of any tools whatsoever. This makes it always convenient for 40 application or use and obviates the necessity of tools which in the hands of a careless operator are liable to injure the bag. It is adaptable in situations where the bags are of varying sizes or thicknesses, for the 45 turn end of the wire is carried along the body of the tie for sufficient length to thus strengthen or thicken the extended portion of the tie. This doubling of the wire permits the use of a relatively light and cheap 50 wire while at the same time I secure in effect

a heavy and thick wire at the point where the wire should be thick and heavy, that is at the point where it is bent. The roughened surface of the tie at this point due to the doubling back of the wire upon itself 60 gives a good grip and tight engagement between the two portions of the tie. The small loop at the free end of the tie furnishes an end without any sharp point to injure the hand or the bag and is of such 65 a nature that it may be finally forced into position close to the bag so as to obviate the danger of being disengaged. It will be observed that the large loop is in effect a slip knot, and excessive pressure on the tie will 70 simply make the loop smaller instead of breaking the wire of the tie. Whereas in the preferred form the return piece of wire is wound around the straight body of the tie the effect is to produce a kind of notched 75 end which when carried through the large loop gives the latter a series of notches in one of which it may find rest so as to give a secure hold.

The tie is particularly adapted for use in 80 connection with ordinary open mouth bags. They can be fed to any machine for application, in the event of their being applied by machinery, by stringing them upon an inclined string by means of one of the loops.

The use and operation will be obvious 85 from what has gone before. The tie is bent around the end of the bag and the small loop passed through the large loop and then it is drawn tightly into position so as to securely 90 clamp or tightly grip the end of the bag. The small loop end of the double-wire end of the tie is then doubled back upon the large loop whereupon the parts are held tightly in position because of the strength 95 of the tie at the point where the wires are doubled, by the roughened or notched character of the tie at this point which gives a good grip, and by the fact that the small 100 loop end can be forced close to the material of the bag.

A is a straight length of wire. B is a round loop at one end thereof, having one end B¹ slidably engaging the body of the tie A.

C is a crooked wire portion integral with the straight portion A, bent back upon it and twisted around it. This crooked twisted portion surrounding the straight portion, stiffens it, and forms in effect a 110

reinforcement which may be passed through the ring B.

I claim:

A wire tie for bags and the like having a loop at one end and bent back upon itself at the other end, so as to form a double-wire portion made up of a straight portion and a crooked portion twisted therearound, and a loop at the other end of the wire formed

by the wire end slidably engaging the body 10 of the wire to leave the loop free to contract.

In testimony whereof, I affix my signature in the presence of two witnesses this 23rd day of December, 1913.

ADELMER M. BATES.
